UNITED STATES PATENT OFFICE.

WENDELL HESS, JR., OF TROY, NEW YORK, ASSIGNOR TO JOSEPH A. LEGGETT, OF SAME PLACE.

STARCHING-MACHINE.

SPECIFICATION forming part of Letters Patent No. 634,346, dated October 3, 1899.

Application filed October 13, 1898. Serial No. 693,421. (No model.)

To all whom it may concern:

Be it known that I, WENDELL HESS, Jr., a citizen of the United States, residing at Troy, county of Rensselaer, and State of New York, 5 have invented certain new and useful Improvements in Starching-Machines, of which the following is a specification.

The invention relates to improvements in starching-machines; and it consists of 10 the novel construction and combination of parts hereinafter described and subsequently claimed.

Reference may be had to the accompanying drawings and the letters of reference marked 15 thereon, which form a part of this specification.

Similar letters refer to similar parts in the several figures.

Figure 1 of the drawings is a view in front 20 elevation of my improved starching-machine. Fig. 2 is a side elevation of the same viewed from the left-hand side shown in Fig. 1. Fig. 3 is a central vertical cross-section of the upper part of the machine. Fig. 4 is an end 25 view of the sectional case for the feed-roll detached and partly opened. Fig. 5 is a plan view of the roll, having an imperforate smooth metal surface detached and without the shade-lines usually employed to indicate a 30 curved surface. Fig. 6 is a similar view of the drum, having a smooth imperforate rubber surface.

A is the main frame of the machine, provided with the supporting-legs A'.

35 B is a clothed drum journaled at each end in a bearing-block B', movable vertically in the slideway A³, formed on the main frame. One of the drum-journals B² projects through its bearing-block and is provided on its projecting end with a gear-wheel B³, fixed thereon and adapted to mesh with and be driven by the gear-pinion B⁴, fixed upon the hub of the drive-pulley B⁵, said pulley and pinion being rotatively supported upon the shaft B⁶, fixed in the frame of the machine. The drive-pulley B⁵ is adapted to receive a driving-belt in the usual manner, whereby comparatively slow rotary movements may be imparted to the drum.

50 C is a cylinder or roll journaled at its ends in the upper part of the main frame, with its

journals C' projecting exteriorly of said frame and each provided with a fixed pulley C², adapted to receive a driving-belt, whereby comparatively rapid rotary movements may 55 be imparted to the roll. The axes of the drum and roll are parallel with each other and they are shown in the same vertical plane. The drum and roll are held in yielding engagement with each other by means of the weight 60 W, which is adjustably movable along the arm of the rock-lever W⁷, fixed upon the shaft W², rotatively supported in bearings in the frame of the machine. This rock-shaft is provided near each end with an offset rock-lever W⁴, connected by a link W⁵ with the movable bearing-block B' on one of the drum-journals. By adjustably moving the weight along its supporting-arm the engaging pressure between the roll and drum can be correspondingly varied.

D is the feed-table, from which the goods to be starched are fed in between the drum and roll. This table is supported by the uprights D' and D', secured to the cross-rod or shaft 75 B⁶ by means of the clamp-plates D² and screws D³, whereby the table can be removed when desired for convenience in cleaning the machine.

H is the delivery table or box, which receives the goods after they have been passed between the roll and drum and which also removes from the periphery of the drum any accumulations of starch which may gather thereon. The delivery-table is provided on its inner edge with a thin metal plate H', adapted to engage the peripheral surface of the drum. The delivery-table is removably secured to and supported by the cross-rod H² by means of the uprights H³, clamp-plates H⁴, and screws 90 H⁵ in the same manner as the feed-table.

Fluid or semifluid starch is deposited upon the feed-table and upon the goods as they are fed from said table by means of the nozzles F, depending from the overhanging supply-pipe F', which leads from the rotary pump F², the pump being operated by means of the belt F³ and pulleys F⁴ on the pump-shaft and F⁵ on the shaft or journal of the feed-roll C. Starch is supplied to the pump through the 100 pipe F⁶ from the starch box or reservoir F⁷, which is located directly beneath the delivery

table or box II, the latter being provided with bottom apertures II⁶, through which the starch which is removed from the drum by the delivery-table returns to the reservoir 5 through its subjacent open top. The several delivery-nozzles are provided with valves F⁸, whereby the supply of starch to the feed-table can be regulated. The pipe leading from the rotary pump is provided with a lateral branch 10 F⁹, leading to the open top of the starch-reservoir F⁷, and a safety-valve F¹⁰ in said lateral branch pipe permits the starch to flow therethrough back into the reservoir when the nozzle-valves F⁸ are closed or when the 15 supply from the pump exceeds the discharging capacity of the nozzles F.

Fresh starch may be supplied to the reservoir as needed.

The feed-roll C is partly inclosed by the 20 sheet-metal case C³, comprising two like approximately cylindrical sections hinged together at C⁴ along their upper edges and provided with end walls C⁵, apertured at C⁶ to receive and fit around the roll shaft or journals. The case is removably secured in position to inclose the roll on the top, front, back, and ends by means of the screws C⁷, inserted through screw-threaded apertures in the frame projections C⁸ and adapted to enter the respective sockets C⁹, formed in the end walls of the case-sections, whereby the case is supported and its sections held together.

The feed-roll C is preferably provided with 35 a polished, smooth, and imperforate metal surface.

The drum is clothed, preferably, with a bed R, of soft rubber, and a covering of one or more plies of thin textile fabric R'. When 40 desired, the fabric covering may be omitted, as shown in Fig. 6.

The feed-roll is operated with a peripheral velocity several hundred times as great as that of the drum, frequently as high as sixteen hundred feet per minute.

The operation of my improved machine is as follows: The goods to be starched are fed in by hand from the feed-table between the roll and drum and delivered upon the delivery-table fully charged with starch. As 45 the goods pass through they do not always or ever occupy the whole space along the line of contact with the feed-roll, so that considerable starch is carried through from the feed-table and deposited on the delivery-table, whence it flows by gravity down into the starch-reservoir, whence it is pumped up to the feed-table, as before described. The speed of the goods is the speed of the peripheral surface of the drum, and the goods are fully and quickly charged with starch in one operation. The peripheral speed of the roll being several hundred times that of the drum and goods each portion of the goods is acted 55 upon hundreds of times in rapid succession and the particles of starch driven into the pores of the fabric with great force. This

high rate of speed is made possible by the lubricating qualities of starch and the smooth even surface of the roll. The amount of 70 starch forced into the goods can be varied by a variation in the relative peripheral speeds of the roll and drum. The yielding surface of the drum permits the goods to be partially embedded in the drum, so that those portions 75 having seams and other normal projections will present comparatively smooth surfaces to the roll, whereby approximately the whole surface of one side of the goods will contact with the roll.

It is preferable to use cold starch in connection with starching apparatus for the reason that if hot starch is employed and allowed to cool on the goods it cannot be easily removed, making it almost impossible to send the goods 80 to the ironing-machine without an uneven deposit on the surface of the goods, which greatly mars their finished appearance. It is, however, well known that hot starch will penetrate the goods much more freely than 85 cold starch, also that the hot starch runs out of the goods more freely.

If sufficient time and effort are expended to work cold starch into goods, they will retain more and be stiffer when ironed than 90 like goods treated with hot starch.

My new method of applying the starch contemplates using cold starch with cold fabric and at the very instant of inserting the starch in the fabric heating those particles of starch 100 which are actually applied and inserted and successively heating the particular parts of the fabric which receive the heated particles of starch.

The parts of starch most heated enter the 105 fabric and are partially cooled before they can escape from it. No particles left on the surface are heated to such a degree as to become sticky or changed in character upon returning to their normal cool temperature. 110 This heat is produced by the friction of the roll slipping upon the goods and the surface-applied particles of starch.

Since the goods are continually traveling with their supporting-drum, the action upon 115 the successive particles is instantaneous and must be considerable to leave the starched goods warm to the touch, as is the case in practice. This friction and the resultant heat can be regulated by varying the speed of the 120 roll and the position of the weight which determines the engaging pressure between the roll and drum or goods on the drum.

Various expedients have heretofore been resorted to for rubbing or beating starch into 125 fabrics, such as rubbing it in with the hand, the use of revoluble beaters, and reciprocating mechanical rubbers.

I have ascertained that a smooth polished starch-feeding roll can be safely rotated in 130 contact with the fabric with a peripheral speed several hundred times greater than that of the fabric, and that such movement of the roll upon the fabric and applied starch

produces an appreciable frictional heat, and that such heat is considerable at the line of contact between the roll and fabric, being sufficient to make quite hot both the fabric 5 and the starch just as they come in contact with each other, so that the fabric is in the best condition to receive the starch and the starch to penetrate the fabric.

I have by actual experiment in practicing 10 my improved method of starching fabrics herein shown and described caused starch to penetrate and fill eight plies of fabric superposed one upon another, the starch entering the eighth ply through the other seven plies.

15 In starching goods composed of two or more plies of fabric, such as collars and cuffs, a surplus of starch is forced through the outer ply or plies next the feed-roll into the space between the plies. The ply or plies next the 20 roll are superheated—that is, made hotter than the plies next the drum—and receive the superheated particles of starch more readily, causing a slight accumulation or surplus between plies of differing temperatures. As the 25 goods advance between the roll and drum the surplus is forced back and out, being wholly expelled and removed from the inner and outer surfaces of the plies by the pressure between the roll and drum as the goods 30 finally pass through. Thus in one continuous operation I am able to apply the starch to the goods, cause it to penetrate and fill the pores of the fabric plies, and remove from the inner and outer surfaces of the plies any 35 surplus of starch. Furthermore, the movement of the goods and the smooth-surfaced feed-roll being continuous and at a uniform speed and pressure, all parts of the goods are uniformly and fully charged with starch and 40 the surplus discharged.

I do not wish to be understood as limiting the carrier of the goods, which is provided with a yielding embedding-surface, to a rotary drum.

45 Any known movement of the bed to carry the goods past the rapidly-rotating feed-roll is within the spirit of my invention. The roll is preferably provided with a smooth imperforate surface to contact with the goods. I 50 have used successfully a roll having a polished bronze surface in engagement with the goods.

In order to expel the surplus of starch from 55 every part of the goods and yet leave every part fully charged with starch, it is necessary that the contact-pressure of the roll and drum should be constant and uniform upon every part of the goods. To secure such constant and uniform pressure, it is desirable that the 60 contacting surfaces of the roll and drum should be smooth and imperforate, and I have ascertained that highly satisfactory results can be obtained by the use of a roll having an imperforate smooth metal surface, as 65 shown in Fig. 5, and a drum having a smooth imperforate rubber surface, as shown in Fig.

6. The rapidity of movement of the roll causes particles of starch which are carried by its surface past the drum to be thrown therefrom with great centrifugal force. To 70 prevent the escape of such starch, I provide the drum or bed with end flanges B⁷ and extend the end walls C⁵ of the roll-case C³ within such end flanges approximately to the peripheral surface of the bed or drum, whereby 75 any starch which escapes from the ends of the roll past the lower edge of the end walls of the case will be arrested by the end flanges B⁷.

What I claim as new, and desire to secure by Letters Patent, is— 80

1. In a starching-machine the combination with a movable fabric-carrier having a yielding embedding-surface, and means for imparting to the carrier comparatively slow carrying movements; of a coöperative charging- 85 roll; means for imparting to the roll a comparatively high rate of peripheral speed; and means for producing and regulating a yielding pressure between the roll and carrier, substantially as described. 90

2. In a starching-machine, the combination with a rotary drum having a yielding embedding-surface, and means for imparting to the drum a comparatively low rate of peripheral speed; of a coöperative feed-roll; means for 95 imparting to the feed-roll a comparatively high rate of peripheral speed; and a feed-table for feeding the starch and goods to the roll and drum, substantially as described.

3. In a starching-machine, a rotary charging and discharging roll; and means for imparting to the roll a comparatively high rate of peripheral speed; in combination with a rotary embedding-drum coöperative with the roll; and means for imparting to the drum a 105 comparatively low rate of peripheral speed; bearings for the drum-journals movable toward and from the roll; and means for producing a yielding pressure between the roll and drum, substantially as described. 110

4. In a starching-machine, the combination with a rotary drum having a yielding embedding-surface; and means for imparting to the drum a comparatively low rate of peripheral speed; of a feed-roll having an imperforate, 115 smooth polished surface coöperative with the drum; and means for imparting to the roll a comparatively high rate of peripheral speed, substantially as described.

5. That improvement in the art of starching fabrics, which consists in charging with a uniform quantity of starch all parts of the fabric, and, at the instant of applying the starch, heating the fabric parts to which the starch is applied and the particles of starch 125 inserted therein, successively and to a comparatively high temperature, substantially as described.

6. That improvement in the art of starching two-ply goods, which consists in heating 130 some particles of the starch and one ply of the goods to a comparatively high tempera-

ture, inserting the superheated starch in the respective plies with a surplus of starch between them, and expelling the surplus from between the plies by pressing the plies together all in one continuous operation.

7. In a starching-machine, the combination with a supporting-bed having end flanges, and means for slowly moving the bed; of a coöperative feed-roll; means for rapidly rotating the roll; and a stationary case for the roll having end walls located within the bed-flanges and extending approximately to the bed, substantially as described.

8. In a starching-machine, the combination with the rotary embedding-drum and feed-roll; a feed-table; and a starch-reservoir; of a receiving table or box having a bottom outlet communicating with the starch-reservoir; a drum-engaging knife on the inner end of the receiving-table; a pump; a supply-pipe leading from the starch-reservoir to the pump; and a delivery-pipe leading from the pump to the feed-table, substantially as described.

9. In a starching-machine, the combination with a starch-reservoir, a pump, a supply-pipe leading from the starch-reservoir to the pump, and a delivery-pipe provided with a valved nozzle; of a lateral branch pipe extending from the delivery-pipe to the starch-reser-

voir; and a safety-valve in said lateral pipe, substantially as described.

10. In a starching-machine, the combination with a feed-roll having an imperforate smooth metal surface; and means for rapidly rotating the roll; of a coöperative drum having an imperforate smooth rubber surface; and means for slowly rotating the drum; and means for producing uniform pressure between the drum and roll, whereby said smooth metal and rubber surfaces coöperate to charge the goods with a surplus of starch and to discharge the surplus, only, from every part of the goods, substantially as described.

11. That improvement in the art of starching fabrics, which consists in mechanically applying cold starch to the fabric, and at the instant of inserting the starch, heating the fabric parts and the particles of starch inserted therein, successively and to a comparatively high temperature, substantially as described.

In testimony whereof I have hereunto set my hand this 7th day of October, 1898.

WENDELL HESS, JR.
